UNITED STATES PATENT OFFICE.

HARRY C. BREWSTER, OF SHREVEPORT, LOUISIANA.

PIPE TONGS.

Application filed June 28, 1922, Serial No. 571,350. Renewed October 3, 1925.

To all whom it may concern:

Be it known that I, HARRY C. BREWSTER, a citizen of the United States, and resident of Shreveport, in the parish of Caddo and State of Louisiana, have invented certain new and useful Improvements in Pipe Tongs, of which the following is a specification.

This invention relates to tongs especially adapted for gripping the pipes and couplings employed in an oil well and the invention is especially designed for use in connection with drilling rotaries of the type illustrated in my several co-pending applications for patent.

An important object is to provide a pipe tong for drilling rotaries having novel means whereby the same may be operated entirely by one man, thereby dispensing with the necessity of employing two pipe tong operators as is now the case.

A further object is to provide a double wrench or two part tong for drilling rotaries having novel means whereby the several wrenches may be rotated in either direction.

A further object is to provide a pipe wrench for oil wells which is of highly simplified construction, safe to use and cheap to manufacture.

Other objects and advantages of the invention will be apparent during the course of the following description.

In the accompanying drawings, forming a part of this application, in which like numerals are employed to designate like parts throughout the same,

Figure 1 is a perspective illustrating the improved double wrench applied.

Figure 2 is a vertical sectional view through the wrench applied.

Figure 3 is a perspective of the bottom wrench.

Figure 4 is a perspective of the upper wrench, the jaws being separated or in their open positions.

Figure 5 is a perspective of one of the top jaws,

Figure 6 is a perspective of a handle embodied in the invention,

Figure 7 is a perspective of one of the jaws forming a part of the top wrench, the same being associated with the jaw illustrated in Figure 5,

Figure 8 is a perspective of one of the jaws of the bottom wrench,

Figure 9 is a perspective of the handle embodied in the bottom wrench,

Figure 10 is a perspective of one of the jaws of the bottom wrench, the same being associated with the jaw illustrated in Figure 8.

In the drawing the numerals 5 and 6 generally designate upper and lower wrenches respectively while the numerals 7 designates pipe sections joined by means of a coupling 8.

The invention forming the subject matter of this application resides in the provision of means whereby the wrenches may be applied to the column formed by the sections 7 entirely by one man and subsequently operated independently of each other so that the upper section 7 may be rotated.

The upper wrench consists of a pair of semi-circular jaws 10 adapted to be arranged about the upper section 7 and having their rear ends formed with radial shanks 11 connected to the ears 12 of the handle 13 through the medium of pivot pins 14.

With reference to Figure 5 it will be observed that the radial shanks 11 are provided with diagonal slots 16 which receive the pivot pins 14. By reason of this construction, when the handle 13 is rotated in one direction one of the jaws 10 will be urged into gripping engagement with the pipe and when the handle is rotated in the other direction, the other jaw will be urged into gripping engagement with the pipe. It is thus seen that the direction of travel of the wrench may be quickly reversed without any adjustment or change in the arrangement of parts. Gripping means 45 are provided on the inner sides of the jaws 10.

Figures 4, 5 and 7 illustrate that the forward ends of the jaws 10 are provided with radial lugs 18 which are adapted to be arranged in parallel relation, as illustrated in Figure 1 and subsequently connected by means of a latch 20 pivoted to one of the lugs. The free end of the latch 20 is provided with an upstanding end portion 21 which may be engaged with the outer edge of one of the lugs 18 in the manner illustrated in Figure 1. This securely and positively holds the jaw 10 in the position illustrated in Figure 1.

The lower wrench 6 is more or less simi-

lar in construction to the upper wrench and consists of a pair of jaws 22 having their inner sides provided with gripping means 45. The rear ends of the jaws 22 are provided with radial shanks 24 having diagonal slots 25 for the reception of pivot pins 26 carried by the ears 27 of the lower handle 28. In this case also the diagonal slots 25 and the pins 26 provide a means whereby either jaw 22 may be securely engaged with the coupling 8.

The forward ends of the lower jaws 22 terminate in radial lugs 33 one of which is provided with a pivoted latch 34 having one end formed with an upstanding portion 35 adapted to engage the free lug.

The upper wrench and more particularly the jaws 10 of the same are provided with depending flanges 40 having their inner sides formed with grooves 41 to receive outwardly projecting flanges 44 of the lower jaws 22. It will be observed that the semi-circular flanges 44 of which there are two are rotatably received in the grooves 41 so that the upper wrench will rotatably support the lower wrench. That is to say the two wrenches are rotatably connected and one of the wrenches may remain stationary while the other wrench may be rotated.

When the top wrench 5 which carries the bottom wrench is open as illustrated in Figure 4 the lower wrench may be detached and used separately if desired.

In use the upper and lower wrenches are rotatably connected and are applied to the pipe as a unit entirely by one person, thereby dispensing with the necessity of employing two attendants as is now the case. The handle 28 of the lower wrench is now engaged with the more or less stationary post of the drilling rotary and the upper wrench and more particularly the handle of the same is rotated about the axis of the post for tightening or loosening the upper pipe section 7. It is thus seen that when applied one of the wrenches may be rotated without interference by the other wrench and when it is desired to detach the wrench it is merely necessary to swing the latches 20 and 34 outwardly to the positions illustrated in Figures 3 and 7.

With reference to the foregoing description taken in connection with the accompanying drawings, it will be apparent that the improved wrench may be economically operated as the number of attendants necessary is reduced to a minimum.

Having thus described the invention, what is claimed is:—

1. A wrench of the character described comprising upper and lower wrenches, each of which is provided with semi-circular jaws having their rear ends formed with shanks provided with diagonal slots, handles having ears provided with pivot pins received in said slots, one of the wrenches being provided with semi-circular flanges having grooves, and the other wrench being provided with semi-circular flanges received in said grooves whereby to connect the wrenches for rotation with relation to each other.

2. A wrench of the character described comprising upper and lower wrenches, each of which is provided with semi-circular jaws having their rear ends formed with radial shanks provided with diagonal slots, handles having ears provided with pivot pins received in said slots, one of the wrenches being provided with semi-circular flanges having grooves, and the other wrench being provided with semi-circular flanges received in said grooves whereby to connect the wrenches for rotation with relation to each other, and radial lugs formed on said jaws and having means whereby the same may be detachably connected.

3. A device of the class described comprising upper and lower wrenches each of which is provided with semi-circular jaws having gripping means, the rear ends of the jaws being provided with radial shanks, handles connected to said shanks, the forward ends of said jaws being provided with lugs, latches pivoted to certain of said lugs and engaging the other lugs whereby to hold the jaws together, the upper wrench being provided with semi-circular depending flanges surrounding the lower jaws and having grooves on their inner sides, and the jaws of the lower wrench being provided with outwardly projecting semi-circular flanges received in said grooves whereby to detachably connect the lower wrench to the upper wrench.

4. A pipe wrench comprising a plurality of pipe gripping units, rotatably fitted within each other, locking means at one end of each unit and combined pressure and rotating means at the opposite end of each unit and arranged to selectively turn the respective units with or against each other.

HARRY C. BREWSTER.
